SNOWSHOE

Frederick T. Paden, Collingswood, N. J.

Application June 24, 1949, Serial No. 3,495

Term of patent 3½ years

(Cl. D34—14)

To all whom it may concern:

Be it known that I, Frederick T. Paden, a citizen of the United States of America and residing at Collingswood, New Jersey, have invented a new, original, and ornamental Design for a Snowshoe, of which the following is a specification, reference being had to the accompanying drawings, forming a part thereof.

Fig. 1 is a top plan view of a snowshoe, showing my new design;

Fig. 2 is a bottom plan view thereof; and

Fig. 3 is a side elevation thereof.

The dotted line showing in Fig. 3 of the shoe-clamping means has been omitted from Figs. 1 and 2 for convenience of illustration.

The dominant features of my new design are shown in solid lines in the drawings.

I claim:

The ornamental design for a snowshoe, as shown and described.

FREDERICK T. PADEN.
